UNITED STATES PATENT OFFICE.

CHARLES M. DAVIS, OF BATTLE CREEK, MICHIGAN.

SHAVING-CUP.

No. 882,668.

Specification of Letters Patent. Patented March 24, 1908.

Application filed January 21, 1907. Serial No. 353,254.

To all whom it may concern:

Be it known that I, CHARLES M. DAVIS, citizen of the United States, residing at Battle Creek, in the county of Calhoun and State 5 of Michigan, have invented certain new and useful Improvements in Shaving-Cups, of which the following is a specification.

My invention relates to shaving cups, and has for its object the production of receptacles adapted to be used to make lather from soap for shaving purposes, the bottoms of which consist of thin metal or thin metal dished in form and capable of being pressed inward by the fingers of the user. In each 15 of such receptacles there is a second bottom or partition, relatively rigid and located above the yielding bottom whereby a chamber is created between those bottoms, and the contents of the chamber may be discharged upwardly into the cup through a suitable orifice in the rigid bottom by pressing upon the yielding elastic lower bottom.

My invention has also for an object the provision of means constructed to permit the 20 filling of the chamber mentioned with sapo- naceous material when it has been exhausted.

I accomplish the stated objects by fashioning and associating the parts as illustrated in the accompanying drawings of which

30 Figure 1 represents a vertical sectional view of my invention. Fig. 2 is a top plan view of the cup with the cover removed. Fig. 3 is a vertical sectional view showing a removable soap or preparation chamber, and 35 Fig. 4 is a plan view of the cup shown in Fig. 3 with the cover removed.

Like reference letters are used to designate the same parts throughout the specification and drawings.

40 The letter A marks the body of the cup, the mouth of which is shown closed by the cover B. The cover may have a threaded engagement with the cup as illustrated, or those threads may be omitted and the cover 45 made to fit the cup in any common manner. The cover B has a central threaded throat b, and the threads of the throat are such as may be engaged by the two separated threaded portions C and D formed upon the handle E 50 of the shaving brush F. The office of the cover B is a double one. In addition to protecting the cup from settling dust or the like, it may be employed as a lather guard. That 55 is to say when the threaded portion C, the lower one, engages the throat of the cover as illustrated in Fig. 1, the lather when in a

too fluid condition and running from the brush is caught in the cover before it reaches the hand of the user. The other threaded portion, D, may also engage the throat, 60 whereupon the brush is in position to reach the bottom of the cup, as shown in Fig. 3.

In Fig. 1, the rigid bottom a of the cup has an integral downwardly extending flange a', and at the lower edge of that flange is suitably secured the flexible and elastic second bottom G. It is thought to be now clear that if the flexible bottom be pressed upwardly any shaving preparation in a fluid or semi-fluid condition, or even in the form of 70 powder with which the space between the two bottoms may be filled, will be forced upwardly into the cup through the perforated projection a².

It will be noted in Fig. 1 that the elastic 75 bottom G is provided with the ordinary round threads and removably engages corresponding threads at the lower edge of the cup. To fill the space between the bottoms with shaving preparations, the bottom 80 G is unscrewed, the cup inverted, the space filled, and the bottom G replaced.

In Fig. 3, the bottom a of the cup, or in other words, the rigid bottom, has no flange. The soap or preparation chamber mentioned 85 hereinabove being now afforded by the interior of the cylindrical box H, to which the flexible bottom G is suitably secured. The box H fits the lower external portion of the wall of cup A sufficiently tight to hold itself 90 thereon yet still be removable when it is desirable to refill the box.

The operation of both forms of this invention is the same, and after a sufficient amount of the preparation has been injected into the 95 cup, the brush is moistened and the lather made in the usual way. Here it will be noted that the perforated projection a² rises a short distance above the bottom of the cup. Its height is designed to be enough to keep 100 the opening of the perforated projection above the ordinary level of fluid in the cup which may be placed therein preparatory to making the lather, and in order that such fluid may not descend into the preparation in 105 the chamber beneath the rigid bottom when that chamber is filled with a dry powder, for example.

Having now described my invention and explained the mode of its operation, what I 110 claim is.—

1. A shaving cup having a removable

cover provided with a threaded throat, and a shaving brush having a handle provided with spaced threaded portions constructed to engage the said throat of the cover separately, the said cover being formed to constitute a lather guard, substantially as described.

2. A shaving cup having a bottom provided with a perforated projection, and a flexible bottom located below the said first mentioned bottom leaving a space between them, the said flexible bottom being constructed to be pressed inwardly with the fingers thereby injecting the contents of the said chamber into the cup, substantially as described.

3. A shaving cup having a bottom provided with a perforated projection, and a box connected with the cup and having a flexible

bottom located below the said bottom of the cup leaving a space between them, the said flexible bottom being constructed to be pressed inwardly with the fingers thereby injecting the contents of the said chamber into the cup, substantially as described.

4. A shaving cup, having an opening leading into it, and means connected with the said cup and including a flexible portion constructed to be pressed inwardly whereby lather-forming material may be injected into the cup through the said opening, substantially as described.

In testimony whereof I affix my signature in presence of two witnesses.

CHARLES M. DAVIS.
